UNITED STATES PATENT OFFICE

137,609

DESIGN FOR A CABINET FOR ELECTRICAL APPARATUS

Soren L. Christie, Los Angeles, Calif.

Application July 17, 1943, Serial No. 110,677

Term of patent 14 years

(Cl. D26—5)

To all whom it may concern:

Be it known that I, Soren L. Christie, a citizen of the United States, residing at Los Angeles, in the county of Los Angeles and State of California, have invented a new, original, and ornamental Design for a Cabinet for Electrical Apparatus, of which the following is a specification, reference being had to the accompanying drawing, forming part thereof.

Fig. 1 is a perspective view of the front and one side of a cabinet for electrical apparatus showing my new design; and

Fig. 2 is a perspective view of the back and other side thereof.

I claim:

The ornamental design for a cabinet for electrical apparatus, as shown.

SOREN L. CHRISTIE.
